UNITED STATES PATENT OFFICE.

SIGMUND STEINER, OF BORYSLAW, AUSTRIA-HUNGARY, ASSIGNOR OF ONE-HALF TO
WOLF KRÖHN, OF BORYSLAW, AUSTRIA-HUNGARY.

APPARATUS FOR RAISING SUNKEN SHIPS.

1,106,983.

Specification of Letters Patent. Patented Aug. 11, 1914.

Application filed November 7, 1913. Serial No. 799,732.

To all whom it may concern:

Be it known that I, SIGMUND STEINER, manager, a subject of the Emperor of Austria-Hungary, residing at Boryslaw, in the 5 Province of Galicia, in the Austro-Hungarian Empire, have invented certain new and useful Improvements in Apparatus for Raising Sunken Ships, of which the following is a specification, reference being had 10 therein to the accompanying drawing.

This invention relates to apparatus for engaging with the decks of sunken ships, whereby the ships may be raised, and if desired conveyed to shallower water.

15 The apparatus is used in connection with a platform, supported over the sunken ship from two other vessels. On the platform a drilling tower is erected capable of movement to all points of the platform and adapted 20 to be fixed in any position. From the drilling tower which is preferably constructed on the well known system of Parker or Raki, tubes are let down through openings in the platform of the sunken ship, and the 25 ship's deck or the sides of the hull are drilled according to one of the said systems. The employment of the Raki drilling system has the advantage of producing a core which shows the nature of the construction of the 30 ship's deck or hull and also shows that the ship has been actually reached.

On the completion of the drilling operation, a gripper is let down through the tubes. This gripper forms the subject matter of 35 the present invention.

An example of the construction of a gripper according to the present invention is illustrated in the accompanying drawings, in which:

40 Figure 1 is a view of the gripper during its descent. Fig. 2 is a view of the gripper showing its parts in their operative position under the deck of the ship engaged thereby, and Fig. 3 is a plan thereof.

45 According to this invention the gripper consists of the rod *a* having an enlargement *b* against which the gripper is adapted to bear by means of a disk *c*.

A ball bearing may be interposed between 50 the enlargement and the disk. Struts *e* are pivoted to the disk *c* by means of joint pins *d*. The other ends of these struts are connected by means of joints *f* to arms *g*. The arms *g* are connect-

ed by means of joint-pins *h* to a disk-like head *i* which engages by means of an internal screw thread with the rod *a* that is formed at this part with a screw thread *k*. This gripper is passed through the tube *l* until its upper edge 60 has moved under the lower edge of the hole previously drilled in the deck of the ship, and in this position its parts are in the positions shown in Fig. 1.

On now rotating the rod *a* which is 65 prevented from vertical movement for this purpose the action of the screw thread *k* will cause the head *i* to move down, while the outer ends of the arms *g* will move against the sides of the tube *l*, and since these ends are formed as cutting edges, or are provided with cutting wheels *o* they will cut through the sides of the tube. As a result of the continued rotation of the 70 bar *a*, the arms will move gradually into 75 the position shown in Fig. 2, carrying with them a strip *m* of the side of the tube.

In order to prevent the gripper from sharing in the rotation of the rod *a*, the lowest guide tube may be formed with a corrugated inner surface, so that the largest diameter will correspond to the diameter of the upper tubes. The rod *a* can now be raised together with the gripper by screwing or the like. The arm *g* bears 80 against the under surface of the drilled part of the ship and will thus act to raise the ship. In order to utilize the guide tubes *l* also for carrying the load, the rod *a* may be provided at intervals with 85 grippers of known construction which jam themselves fast against the inside of the tube and thus cause the rod and the tube to constitute a common supporting device. If desired a number of grippers may be arranged 90 on one and the same rod at such distances apart as to enable a number of superposed parts of the deck of the sunken ship to be 95 engaged thereby.

By making the parts of the apparatus of 100 suitable strength, and by providing a sufficiently large number of points of engagement with the sunken ship, the latter may be raised from the bottom and then while thus suspended be conveyed to any desired 105 point together with the vessels supporting the same which are connected by the platform.

Having fully described my invention, what I claim as new, and desire to secure by Letters Patent, is—

1. In a gripping device for a hoisting apparatus, the combination with a rod, of relatively movable members mounted thereon, a plurality of pairs of gripping members, the members of each pair bearing pivotally against said relatively movable members at their outer ends and being pivotally connected at their inner ends by a pin passing through both members.
2. In a gripping device for a hoisting apparatus, the combination with a rod, of relatively movable members mounted thereon, means carried by said rod to cause relative movement between said relatively movable members upon rotation of said rod, pivotally jointed gripping members bearing pivotally against said relatively movable members, and adapted to be moved outwardly into gripping position upon rotation of said rod.
3. In a hoisting apparatus, the combination with a tube of a gripping device adapted to be lowered therein, comprising a rod, relatively movable disks on said rod, and jointed rods pivoted to said disks, carrying cutting means adapted to cut through said tube and move outwardly when said disks are moved toward each other.
4. In a hoisting apparatus, the combination with a tube of a gripping device adapted to be lowered therein, comprising a rod,

relatively movable disks on said rod, adapted to move relatively upon rotation of said rod, and jointed rods bearing pivotally against said disks adapted to be moved outwardly without rotating when said disks are moved toward each other.

5. In a hoisting apparatus, the combination with a tube of a gripping device adapted to be lowered therein, comprising a rod, relatively movable disks on said rod, and jointed rods pivoted to said disks, carrying cutting means adapted to cut through said tube, move outwardly and carry sections of said tube therewith, when said disks are moved toward each other.

6. In a hoisting apparatus, the combination with a tube of a gripping device adapted to be lowered therein, comprising a rod, relatively movable disks on said rod, adapted to be moved relatively upon rotation of said rod, and jointed rods carrying cutting means bearing pivotally against said disks adapted to cut through said tube, move outwardly and carry sections of said tube therewith, without rotating when said disks are moved toward each other upon rotation of said rod.

In testimony whereof I have affixed my signature in presence of two witnesses.

SIGMUND STEINER.
